UNITED STATES PATENT OFFICE

EUGENE CHARLES BAECK, OF LAKE RONKONKOMA, NEW YORK

PRINTING MACHINE

Application filed April 9, 1930. Serial No. 442,934.

This invention relates to improvements in printing machines, and has especial reference to an ink or color distributor therefor.

5 An object of the invention is the provision of improvements in a printing machine, whereby multi-color work such as the production of wall paper, may be accomplished efficiently, and whereby the resulting products will be characterized by refined print in which the coloring matter or ink will be evenly and uniformly distributed throughout.

15 Another object of the invention is the provision of improvements in a printing machine whereby numerous appurtenances, such as ink spreading devices or rollers, may be omitted, and whereby unnecessary adjustments and consequent delays may be avoided.

25 Another object of the invention is the provision of a fluid ink or color distributor for printing machines which will distribute the ink or color evenly and uniformly directly to the printing surface of a printing roll.

30 The nature of the invention and its distinguishing features and advantages will appear when the following specification is read in connection with the accompanying drawings, in which

35 Figure 1 is a side elevation of one end of a wall paper printing machine embodying the features of the invention;

40 Figure 2 is a vertical section of an ink distributor constructed in accordance with the invention;

45 Figure 3 is a plan view of one end of the fountain of the ink distributor shown in Figure 2.

In Figure 1 of the drawings there is shown one end of a wall paper printing machine which is selected to illustrate the device of the invention. The invention contemplates the provision of separate ink distributors, one for each color, which transfers the ink or color to the related printing roller. The ink or color distributors are arranged in the machine at regular spaced intervals. In Figure 1 of the drawings two

ink or color distributors 10 are shown. Each distributor 10 feeds or distributes ink to the printing surface of a printing roll designated 11, which prints on the paper 12 fed thereto from a roll indicated at 13. A 55 compression roll 14 and endless web 15 co-operate with each one of the printing rolls 11 to obtain the desired pressure. Each of the printing rolls is positively driven by any suitable means such as the employment of gears secured to the shafts of the printing rolls, and a drive chain 16 which co-operates therewith. Each ink or color distributor 10 comprises a fountain 17 and an ink or color feeder or distributor 18. The fountain 17 65 comprises a receptacle or tray 19 of the proper proportion, and is made of any suitable material, such as sheet metal, and a second receptacle or tray 20 of the same general proportions as the tray 19. The tray 19 has 70 an outer rim 21, and the tray 20 has an outer rim 22 which is adapted to rest on the rim 21 to support the tray 20 on the tray 19. The bottom 23 of the tray 20 is formed of a piece of textile material or fabric which is 75 secured in place in any practical manner such as by the employment of a band 24. The bottom 23 is treated with a suitable liquid-proofing substance to render the same impervious to liquid. A pad 25 is arranged 80 within the tray 20 and rests in contact with the fabric bottom 23, and is adapted to absorb the fluid ink or coloring used so as to remain saturated. To this end the pad 25 will consist of an outer textile envelope 26 85 which is filled with suitable absorbent material 36, such as cotton or other cellular material of a kindred nature. It will therefore be understood that the pad 25 will have the power of imbibition. The upper surface of the pad 25 is preferably convex, as shown most clearly in Figure 2. The pad 25 is provided along the opposite side edges thereof with tabs 27 to respectively engage hooks 28 extending laterally from the opposite sides of the tray 20 on the inside thereof. It will therefore be understood that the pad 25 will be prevented from sliding sidewise, and that it may be readily removed from the tray 20. It will also be ap- 90 95 100

parent that the pad 25 is resiliently supported or mounted due to the fact that it rests directly on the flexible fabric bottom 23. In order to supplement the resilient effect of the fabric bottom 23, a quantity of water 29 is put into the tray 19.

In accordance with another feature of the invention, the fluid ink or color is fed or delivered into the tray 20 from a suitable source of supply by one or more inlet pipes 30. In order to maintain the ink or color at a predetermined level below the uppermost surface area of the pad 25 there is provided one or more overflow pipes 31 in communication with the interior of the tray 20. The feeder or distributor 18 is in the form of a roll mounted for rotation so that its cylindrical surface will roll in direct contact with the pad 25 throughout the length of the roll. It is to be understood that the feeder or distributor 18 may be adjusted with respect to the pad 25 so as to exert sufficient pressure on the pad 25, to take up the proper amount of ink or color from the pad 25. In Figure 2 of the drawing the ink or color is indicated at 32, a supply of which is constantly maintained in the tray 20 to keep the pad 25 saturated. The feeder or distributor roll 18 is in contact with the printing surface of the printing roll 11 and the former is rotated by the latter. It will therefore be understood that the ink or color will be distributed over the printing surface of the printing roll 11 from the roll 18.

From the foregoing it will be apparent that the ink or color will be distributed to a printing surface of a printing roll evenly and uniformly without requiring additional means such as ink spreading devices or rolls for this purpose. It will also be apparent that by providing the overflow means in the form of a pipe or pipes 31, ink or color will not pass directly to the periphery of the feeder or distributor roll 18. It will also be apparent that by providing the water beneath the fabric bottom 23 of the tray 20, a proper cushioning or resilient action will be maintained in conjunction with the pad 25, for the purpose of obtaining the proper co-operation of the pad 25 with the feeder or distributor roll 18. By reason of the fact that the fabric bottom 23 is treated with a liquid-proofing composition, the water in the tray 19 will be prevented from mixing with the ink or color in the tray 20.

Claims:

1. In an ink distributor for printing machines, the combination of an ink tray having a bottom made of flexible material, an absorbent pad resting on said bottom and immersed in the ink in the tray, and an ink distributor in rolling contact with said pad.
2. In a liquid ink or color distributing device for printing machines, the combination of a tray for the ink or color, said tray hav-

ing a bottom made of flexible material, a second tray on which the first tray is superposed, said second tray having a quantity of liquid therein level with said bottom, an absorbent pad resting on said bottom and partly immersed in the ink or color in the first tray, and a distributor in rolling contact with said pad, for the purpose of distributing ink or color from the pad to a printing surface.

3. In an ink distributor for printing machines, the combination of an ink tray having a bottom made of flexible material, an absorbent pad resting on said bottom, and immersed in the ink in the tray, and yieldable means cooperating with said bottom to resiliently support said pad.

4. In an ink distributor for printing machines, the combination of an ink tray having a bottom made of liquid-proof fabric, an absorbent pad resting on said bottom, and immersed in the ink in the tray, and a container having liquid therein, and said liquid cooperating with said bottom to resiliently support said pad.

5. In a liquid ink or color distributing device for printing machines, the combination of a tray for the ink or color, said tray having a bottom made of flexible material, a second tray on which the first tray is superposed, said second tray having a quantity of liquid therein level with said bottom, and an absorbent pad resting on said bottom and partly immersed in the ink or color in the first tray.

6. In an ink distributor for printing machines, the combination of an ink tray having a bottom made of flexible material, an absorbent pad resting on said bottom and immersed in the ink in the tray, and cooperative and detachable members on the tray and pad to keep the pad from slipping relative to said bottom and allowing the pad to be removed from the tray.

7. In an ink distributor for printing machines, the combination of a receptacle having liquid therein, an inking pad, and means coacting with said liquid to resiliently support said pad.

8. In an ink distributor for printing machines, the combination of a receptacle having fluid therein, an absorbent pad, means coacting with said fluid to resiliently support the pad, and means to deliver fluid ink to said pad to saturate it.

9. In an ink distributor for printing machines, the combination of a receptacle having liquid therein, an inking pad, and means coacting with said liquid to resiliently support said pad, said means including a flexible sheet which is impervious to liquid and on which said pad rests; and said sheet being disposed on the surface of said liquid.
